ABSTRACT OF THE DISCLOSURE

A process for preparing overbased barium hydrocarbon sulfonate featuring the use of barium sulfide as the barium source. The product obtained from this process and diesel fuel containing a smoke reducing quantity of this product are described.

BACKGROUND OF THE INVENTION

This invention is directed to a method of preparing overbased barium sulfonates and their use in distillate fuels.

Processes for preparing overbased alkaline earth oil soluble sulfonates are available in the art (see e.g. U.S. 2,617,049, U.S. 2,956,018, U.S. 3,027,325, and U.S. 3,312,618). The principal products disclosed in the art appear to be those prepared from petroleum derived sulfonic acids. These petroleum derived sulfonic acids are in general alkaryl sulfonates obtained as side products from the sulfuric acid treatment of petroleum hydrocarbons in refining operations.

The term overbased indicates that the resultant product from these various processes contains an amount of alkaline earth metal greater than the stoichiometric amount of metal which would be present if the particular sulfonic acid were fully neutralized. The theory of this overbased complex formation is not fully understood. One suggestion has been that the oil soluble sulfonates act as protective colloids or dispersants thus keeping an alkaline earth compound suspended in a fluid carrier.

A general method of preparing these complexes features the in situ formation of a finely divided alkaline earth compound such as CaCO_3 , in the presence of a petroleum sulfonate in a hydrocarbon medium. This is accomplished by introducing an acidic gas such as carbon dioxide into an alkaline earth containing, petroleum sulfonate dispersion in a hydrocarbon medium. Recent improvements in this process feature the use of promoters such as low molecular weight alcohols, phenols, amines, and the like.

The present invention provides a method of preparing overbased barium sulfonates featuring the use of barium sulfide as the barium source. The products are effective smoke suppressors in diesel fuels.

SUMMARY OF THE INVENTION

A process for preparing overbased barium sulfonates from a sulfonic acid material, barium sulfide, and carbon dioxide in the presence of $\text{C}_1\text{--C}_5$ alkanol and water in a hydrocarbon medium; the product obtained by this process and its use as a smoke reducing diesel fuel additive.

DESCRIPTION OF THE PREFERRED EMBODIMENTS

A preferred embodiment of this invention is a process for preparing an overbased barium sulfonate which comprises:

(1) preparing a slurry of barium sulfide in from about 100 to about 800 parts by weight of $\text{C}_1\text{--C}_5$ alkanol per mole of barium sulfide, adding at least an equimolar amount of water based on barium sulfide, and heating

2

said mixture to a temperature from about 50° C. to the reflux temperature,

(2) adding thereto a mixture of an inert hydrocarbon medium and a sulfonic acid material selected from:

5 (a) $\text{C}_{12}\text{--C}_{17}$ alkyl benzene sulfonic acids, and
(b) sulfonated olefin derivatives prepared by sulfonating mixtures of acyclic, monoolefins having

from about 14 to about 30 carbon atoms,

such that the molar ratio of barium sulfide to said

10 sulfonic acid material is from about 1:1 to about 10:1,

(3) introducing carbon dioxide gas into the heated mixture of Step (2) until substantially no hydrogen sulfide is evolved from said mixture, and

(4) distilling said alkanol and water from said mixture.

15 Another preferred embodiment of this process features the use of sulfonated olefin derivatives prepared by sulfonating a C_{18+} olefin whose specific composition is given below. Dodecyl benzene sulfonic acid is used in a most preferred embodiment. Barium sulfide in the crude form known as "black ash" is a most preferred form of BaS .

Sulfonic acid materials of various types may be used in the present process. These include alkenyl sulfonic acids, alkyl sulfonic acids, hydroxy alkyl sulfonic acids, sulfones, mixtures thereof, as well as alkyl benzene sulfonic acid.

20 Hydrocarbon soluble petroleum sulfonic acids, the so-called "mahogany" sulfonic acids, are also useful in this process. These "mahogany" sulfonic acids are mixtures of sulfonic acids obtained during sulfuric acid treatment of petroleum refinery streams.

25 Sulfonic acid containing products obtained on sulfonating olefins are another type of useful sulfonic acid material. These products are referred to herein as sulfonated olefin derivatives. By olefins I mean hydrocarbon olefins.

30 The products obtained on sulfonating acyclic monoolefins having from about 14 to about 30 carbon atoms are particularly useful. Especially useful olefin starting materials are the mixtures of acyclic olefins obtained from

35 synthetic manufacturing processes such as dehydrogenation of paraffins or polymerization of low molecular weight olefins such as ethylene and propylene. Synthetically prepared monoolefins having the following olefin makeup and configurations (double bond position) are most preferred; the olefins are predominantly alpha. These mixed olefins are identified herein as C_{18+} olefins.

Olefin chain length:	Percent by weight ¹
C_{16} and lower	0-3
C_{18}	0.5-17
C_{20}	33-52
C_{22}	19-37
C_{24}	9-15
C_{26}	2-7
C_{28+}	0-8

45 ¹ Vapor phase chromatography analysis.

Olefin configurations ² :	Percent distribution
Vinyl	32-54
Internal	12-31
Vinylidene	32-47

50 ² Nuclear magnetic resonance analysis.

In sulfonating olefins, any suitable sulfonation procedure may be utilized. Suitable procedures are described in the following patents: U.S. 3,259,645; U.S. 3,337,437; British 1,072,601; French 1,403,407 and French 1,399,570.

55 In general, the sulfonation of olefins comprises treating olefins with a sulfonating agent such as SO_3 , to produce a sulfonated derivative.

The mixtures of useful olefins contain varying ratios and combinations of olefins having from about 14 to about 30 carbon atoms. These mixtures may contain linear olefins, branched olefins, and mixtures thereof.

Representative examples of monoolefin mixtures from which preferred sulfonated olefin derivatives are prepared are presented in the following table; the mixtures contain more than about 60 percent α -olefins.

TABLE 1.—PREFERRED OLEFIN MIXTURES

Olefin:	Percent by weight							
	A	B	C	D	E	F	G	H
C ₁₂	0.3							
C ₁₄	26.5	0.1			9	1	0.1	
C ₁₆	58.0	0.1	35	40	3	2		0.3
C ₁₈	12.9	21.3	38	35	25	14	20	0.5
C ₂₀			24	3	42	31	33	55
C ₂₂				14.1	2	11	29	32
C ₂₄					18.7	1	9	11
C ₂₆						6	6	15
C ₂₈						9.4	2.5	3
C ₃₀						4.6	0.5	0.9
C ₃₂						1.7		0.1
Non-olefins		2.3		3			5	

Blends of these mixtures are also useful. A blend of seven volumes of mixture A and eleven volumes of mixture B is a particularly useful blend.

Especially useful olefin sulfonation processes and the mechanisms involved are described in the journal "Hydrocarbon Processing," vol. 47, No. 3, pages 109-114, March 1968. The material therein described is incorporated by reference. When sulfonating olefins, the products obtained may be mixtures containing alkenyl sulfonic acids, hydroxyalkyl (or -alkenyl) sulfonic acids, and 5 and 6 membered ring inner esters called sultones. These sultones may comprise as high as 50 percent of the sulfonated olefin product when using a falling film reactor system. The sultones are readily saponified by treatment with a strong base. Thus, when sulfonated olefin products are used as the hydrocarbon sulfonic acid material in the present process, it is desirable to saponify this product so that the full sulfonic acid value of the material is realized in the process. The saponification can be carried out prior to the overbasing step in the process. By overbasing step is meant the point at which carbon dioxide is introduced into the reaction mixture to form barium carbonate in situ. This saponification can be carried out by treating the sulfonated olefin product with a strong base such as sodium hydroxide or potassium hydroxide and heating to an elevated temperature for a few minutes. This saponification would yield the sodium or potassium salt of all the sulfonic acids present. It would be better then to convert this salt to the corresponding barium salt for use in the present process.

A more preferred procedure is to saponify the sultone containing sulfonated olefin derivative with barium oxide or barium sulfide/water as the first step in the process and then to continue with the overbasing step.

A most preferred way of saponifying the sultone is to charge the sulfonated olefin derivative, the hydrocarbon medium, and the barium sulfide-water-alcohol ingredients into the reactor and then heat this mixture to effect the saponification while bubbling the carbon dioxide through the mixture. This saponification step is an important feature of the process when sulfonated olefin derivatives which may contain sultones are used as a starting material.

Alkylbenzene sulfonic acids wherein the alkyl group has 12 to 17 carbon atoms are also useful. Laurylbenzene sulfonic acid, heptadecylbenzene sulfonic acid, hexadecylbenzene sulfonic acid, tetradecylbenzene sulfonic acid and the like are examples of useful sulfonic acids. Mixed alkylbenzene sulfonic acids prepared for example from the hydrocarbon product of the Friedel Crafts alkylation of benzene with an olefin containing principally tetrapropylene, are another example of a useful sulfonic acid. The useful alkyl benzene sulfonic acids are also characterized by having a molecular weight of less than about 400.

Dodecylbenzene sulfonic acid is an especially preferred alkylbenzene sulfonic acid.

Barium sulfide is the reactant utilized in the present

process to supply the barium values for the overbased product. A preferred form of barium sulfide is a crude product obtained in the commercial preparation of barium sulfide by reducing a barium sulfate¹ with carbon. This crude product is commonly called black ash; it contains up to about 90 percent barium sulfide.

Typical analysis of commercial black ash is as follows; all percentages are by weight.

Black ash typical analysis	
	Percent
Assay BaS	71.2-88.0
Insoluble material	19.2-10.4
Calcium and strontium (as oxides)	0.5
Silica	0.4
Aluminum and iron (as oxides)	1.5
Carbon	3.7
Magnesium (as oxide)	0.2
Thio and other reducible sulfur compounds	2.8

The reaction of the present process is carried out in a suitable hydrocarbon medium. The medium is characterized by being (1) inert during the process of the reaction and (2) a solvent for the sulfonic acid starting material. It is also preferred that this medium be a solvent for the overbased product which is obtained in the process; and this hydrocarbon medium should be compatible with diesel fuel. Any hydrocarbon which meets these criteria may be used. Aromatic hydrocarbons, paraffinic hydrocarbons, olefinic hydrocarbons, mixtures thereof, light distillate hydrocarbon oils, distillate fuels, kerosene, straight run naphtha, petroleum refinery streams such as catalytic reformate, thermally or catalytically cracked streams, alkylated refinery streams, catalytically cracked naphtha and the like, are useful hydrocarbon media. Benzene, C₁-C₈ alkylbenzenes such as toluene, xylene, acetylbenzene, pentylbenzene and the like, C₆-C₁₂ paraffins such as hexane, heptane, dodecane and the like, aviation alkylate, light processing oils such as No. 9 oil and the like, catalytic reformate containing over about 70 percent aromatic hydrocarbons and the like, and mixtures thereof are some examples of useful media.

The amount of hydrocarbon medium used in the process is not critical. An amount of inert hydrocarbon ranging from about 0.5 to about 10 times the weight of the sulfonic acid material can be used.

Alkanols having from about 1 to about 5 carbon atoms are used in the present process. The exact function of the alkanol used in the process is not understood; however, the alkanol is required in order for the reaction of the present process to be carried out. Examples of useful alkanols are ethanol, isopropanol, pentanol-3, amyl alcohol, butyl alcohol, and mixtures of these alcohols. Methanol is a most preferred alkanol.

The amount of alkanol used may be varied. Generally the barium sulfide reactant is dispersed in the alkanol as an initial step. The amount of alkanol used is based on the amount of barium sulfide used. Thus, amounts of alkanol ranging from about 100 to about 400 parts by weight per mole (167 parts by weight) of barium sulfide are generally used.

Water is also required in the present process. At least an equimolar amount of water based on the barium sulfide used is necessary. A larger amount of water, for example up to 2 times the necessary amount, can also be used. The water (and alkanol) has to be distilled off as a final step in the process. As a practical matter then, too large an excess of water is not used.

The amount of barium sulfide used in the present process must be more than the stoichiometric amount required to neutralize the sulfonic acid supplied by the sulfonic acid material. One mole of barium sulfide will neutralize two moles of a sulfonic acid. Thus, the stoichiometric relationship in moles of sulfonic acid to moles of barium

5

sulfide is 2:1. Since the product obtained in the present process is overbased, that is, contains more than the stoichiometric amount of barium, a greater than stoichiometric amount of barium sulfide must be used in carrying out this process. Molar ratios of sulfonic acid to barium sulfide of from 1:1 up to about 1:10 can be used. Ratios of from about 1:2 to about 1:5 are preferred.

The process is carried out at elevated temperatures. Reaction temperatures ranging from about 50° C. up to the reflux temperature of the reaction mixture are used. The reflux temperature, of course, will be dependent upon the particular hydrocarbon medium used, its amount, and the amount of alkanol and water in the reaction mixture. An upper temperature limit would be about 150° C. This reaction temperature is the temperature at which the carbon dioxide is passed into the solution to effect formation of the overbased complex.

The mixture containing the sulfonic acid material in hydrocarbon medium, BaS, H₂O, and alkanol is subjected to treatment with carbon dioxide gas; this is the overbasing step. The CO₂ is simply bubbled through the mixture at the aforesaid reaction temperatures until substantially no H₂S gas is evolved from the mixture. At this point the reaction is considered complete. Any means of detecting the presence of H₂S in the effluent gas coming from the mixture can be used to determine this point; a convenient method is to test the effluent gas with wet lead acetate paper. The treatment with CO₂ effectively complexes the stoichiometric excess of barium sulfide (converted to barium carbonate) with the neutralized sulfonic acid, thus forming an overbased barium sulfonate.

The process of this invention is ordinarily carried out at atmospheric pressures. However, it can also be carried out at pressure above atmospheric. The use of pressures above atmospheric can be used to advantage to minimize solvent loss while carrying out the reaction; higher pressures might also be desirable when a reaction temperature higher than the reflux temperature is used to carry out the reaction. The following examples illustrate the process of the present invention; all parts are by weight unless otherwise indicated.

EXAMPLE 1

A vessel fitted with stirrer, thermometer, water collector, and condenser is charged with 100 parts (0.5 mole) of 85 percent assay barium sulfide and 300 parts methanol. This slurry is stirred and about 9 parts (0.5 mole) of water was added; the mixture was heated to 55–60° C. and kept at this temperature for 50 minutes. A solution of 59.8 parts (0.2 mole) of dodecyl benzene sulfonic acid in about 220 parts of xylene was added and the mixture was refluxed for 30 minutes (hydrogen sulfide was evolved). A stream of carbon dioxide gas was then bubbled through the mixture until evolution of hydrogen sulfide had essentially stopped (5 hours). The methanol and water were then distilled from the mixture (about 44 parts of xylene containing about .8 part of dimethyl formamide was added during the distillation). The mixture was cooled and then diluted further with about 310 parts of benzene containing about .8 part of dimethyl formamide. The solution was then filtered twice and the benzene and a portion of the xylene were distilled off under vacuum. The product at this point gelled on cooling. The product was diluted again with benzene (about 180 parts) and dimethyl formamide (about 2.5 parts). The solution was stirred and then the benzene was distilled off under vacuum. 229 parts of a slightly viscous, clear product were obtained. About 0.8 part of dimethyl formamide was added to the product to reduce its viscosity.

Analysis of the overbased barium sulfonate product showed that it contained 23.6 percent barium and 2.4 percent sulfur.

EXAMPLE 2

Example 1 is repeated substituting 0.05 mole of heptadecylbenzene sulfonic acid for the dodecylbenzene sulfonic

6

acid, 50 parts of isopropanol for the method and toluene for the xylene; the reaction mixture is heated to about 50° C. while the carbon dioxide is bubbled into it.

An overbased barium sulfonate product is obtained.

EXAMPLE 3

A vessel fitted with a stirrer, thermometer, water collector, and condenser was charged with 100 parts (0.5 mole) 85 percent assay barium sulfide and 300 parts of methanol. This suspension was stirred and about 9 parts (0.5 mole) of water were added, followed by a solution of 59.8 parts (0.2 mole) dodecylbenzene sulfonic acid in 75 parts pale oil (Sun Circo XXX Lt) and 170 parts naphtha (aviation alkylate). This mixture was refluxed for 30 minutes and then carbon dioxide was passed through the mixture for 5.5 hours. The methanol and water were then distilled off; about 80 parts naphtha were added during this distillation period. The mixture was cooled and it was further diluted with about 270 parts of hexane. The solution was then filtered; the filtrate was stripped of solvents under vacuum. 224.3 parts of a very dark, slightly hazy viscous liquid product were obtained.

Analysis of this product showed it to contain 28.1 percent barium, 3.1 percent sulfur.

Similar results are obtained when mahogany sulfonic acid is used in place of the dodecyl benzene sulfonic acid. Using black ash to provide an equivalent amount of barium sulfide also produces an analogous product. The reaction of Example 2 is carried out with similar results when ethanol, isopropanol or amyl alcohol is used in place of the methanol. Similar results are obtained when the reaction in Example 3 is carried out in benzene, kerosene, hexane, toluene, and a mixture of No. 9 oil and xylene.

EXAMPLE 4

A vessel fitted with a stirrer, thermometer, water collector and condenser is charged with 100 parts (0.5 mole BaS) of black ash (84.5 percent barium sulfide) about 400 parts methanol. About 9 parts (0.5 mole) of water is added to the stirred slurry and the mixture is heated to about 60° for about one hour. To this suspension is added a solution of 97.4 parts (0.08 mole) of a sulfonated C₁₈– olefin derivative in about 450 parts of xylene; this mixture is then refluxed for about 30 minutes. Carbon dioxide gas is then bubbled through the mixture until substantially no hydrogen sulfide is evolved from the reaction mixture (detectable by lead acetate paper). The methanol and water are distilled off. The mixture is then diluted with about 400 parts of benzene. This solution is filtered. The product obtained is an overbased barium sulfonate.

An analogous product is obtained when the process of Example 4 is carried out under pressure at a temperature of 150° C.

The sulfonated C₁₈– olefin derivative used in Example 4 is a product obtained on sulfonating an olefin mixture having the general composition disclosed above. In order to determine the sulfonic acid content and the sultone content of this derivative, its acid number and its saponification number are determined. The difference between the saponification number and the acid number represents the amount of sultone present in the sulfonated derivative. If a substantial portion of the product is sultone then a saponification step using barium oxide or barium sulfide and water as herein described may be used in carrying out the process of Example 4 more efficiently.

The products of the process of this invention as illustrated by the examples above, are especially useful as smoke reducing additives in diesel fuel. Another embodiment of this invention is a diesel fuel containing a smoke reducing quantity of a product made by the process of the present invention. The amount of such product added to a diesel fuel ranges from about 0.05 percent by weight to about 3 percent by weight of the fuel.

The products obtained by the process of the present invention as illustrated in the above examples are especial-

ly useful as smoke suppressors in distillate hydrocarbon fuels used in diesel engines, and can be added to any commercial diesel fuel. In general these fuels are characterized as having a boiling range of 350° F. to 700° F. So-called residual oils having higher boiling points than this are sometimes blended with a lower boiling diesel fuel. Suitable diesel fuel oils are Federal Specification VV-F800 Grades DF-A, DF-1, DF-2 and DF-4, as well as ASTM Classes 1, 2, 3, and 4. Marine diesel fuel oils are also useful. A tabulation and discussion of suitable diesel fuel oils is presented in "Fuels and Lubricants," Milosh Popovich and Carl Hering, pages 134; 146-151, John Wiley and Sons, Inc., New York (1959).

Following are examples of diesel fuel compositions of this invention.

EXAMPLE 5

A diesel fuel composition is prepared by adding 0.05 percent by weight of the product of Example 2 to a Class 1 diesel fuel oil.

EXAMPLE 6

A diesel fuel composition is prepared by adding 3 percent by weight of the product of Example 1 to Grade DF-3 diesel fuel oil.

EXAMPLE 7

A diesel fuel composition is prepared by adding 1.5 percent of the product of Example 3 to a Class 2 diesel fuel oil.

EXAMPLE 8

A diesel fuel composition is prepared by adding 0.2 percent by weight of the product of Example 4 to Grade DF-2 diesel fuel oil.

EXAMPLE 9

A diesel fuel composition is prepared by adding 0.6 percent by weight of the product of Example 2 to a marine grade diesel fuel oil.

The fuel compositions of the present invention produce less exhaust smoke than the same base fuel containing none of the overbased barium sulfonate products of the present invention. For example, noticeably less smoke is emitted from a diesel engine when it is operating on the fuel composition of Example 6 than when it is operating on Grade DF-3 diesel fuel containing no overbased barium product. Thus, the tendency of a diesel engine to produce exhaust smoke is substantially reduced when a diesel fuel containing the overbased product prepared by the process herein described is used as a fuel.

The present invention therefore is encompassed in three embodiments,

- (1) a process for preparing overbased barium sulfonate products,
- (2) the overbased barium sulfonate product, and
- (3) diesel fuel containing a smoke reducing quantity of this product.

All three embodiments have been described in the foregoing disclosure; it is desired to limit this invention only within the spirit and scope of the following claims.

I claim:

1. A process for preparing an overbased barium sulfonate which comprises:

- (1) preparing a slurry of barium sulfide in from about 100 to about 800 parts by weight of C₁-C₅ alkanol

per mole of barium sulfide, adding at least an equimolar amount of water based on barium sulfide, and heating said mixture to a temperature from about 50° C. to the reflux temperature,

2. The process of claim 1 wherein said barium sulfide medium and a sulfonic acid material selected from:

- (a) C₁₂-C₁₇ alkyl benzene sulfonic acids, and
- (b) sulfonated olefin derivatives prepared by sulfo-

nating mixtures of cyclic, monoolefins having from about 14 to about 30 carbon atoms, such that the molar ratio of barium sulfide to said sulfonic acid material is from about 1:1 to about 10:1,

(3) introducing carbon dioxide gas into the heated mixture of Step (2) until substantially no hydrogen sulfide is evolved from said mixture, and

- (4) distilling said alkanol and water from said mixture.

2. The process of claim 1 wherein said barium sulfide is a crude barium sulfide.

3. The process of claim 1 wherein said sulfonic acid material is said alkylbenzene sulfonic acid and wherein the said molar ratio of barium sulfide to sulfonic acid is from 1:1 to about 5:1.

4. The process of claim 1 wherein said sulfonic acid material is a sulfonated olefin derivative prepared by sulfo-

nating a mixture of acyclic monoolefins comprising by weight 0-3% C₁₆ and lower olefins 0.5-17% C₁₈ olefins,

33-52% C₂₀ olefins, 19-37% C₂₂ olefins, 9-115% C₂₄ ole-

fins, 2-7% C₂₆ olefins and 0-8% C₂₈ and higher olefins

and wherein the distribution of olefin configurations in

said mixture is 12-31% internal, 32-54% vinyl and 32-

47% vinylidene, and wherein said ratio of barium sulfide to said sulfonated olefin derivative is from 1:1 to about

5:1.

5. The process of claim 3 wherein said sulfonic acid

35 is dodecyl benzene sulfonic acid, said hydrocarbon me-

diuum is selected from xylene, light hydrocarbon oils, naph-

tha, aviation alkylate, and hexane, said alkanol is metha-

anol and wherein the molar ratio of barium sulfide to do-

decyl benzene sulfonic acid is about 2.5:1.

6. The product prepared by the process of claim 1.

7. The product prepared by the process of claim 2.

8. A diesel fuel containing a smoke reducing quantity of the product prepared by the process of claim 1.

9. A diesel fuel containing a smoke reducing quantity of the product prepared by the process of claim 4.

10. A diesel fuel containing a smoke reducing quantity of the product prepared by the process of claim 5.

UNITED STATES PATENT OFFICE
CERTIFICATE OF CORRECTION

Patent No. 3,694,175 Dated September 26, 1972

Inventor(s) Charles E. Marble

It is certified that error appears in the above-identified patent and that said Letters Patent are hereby corrected as shown below:

Claim 1, Column 8, line 5 - the correct phrase should read -- (2) adding thereto a mixture of an inert hydrocarbon -- instead of as shown in the patent.

Claim 1, Column 8, line 9 - "cyclic" should read -- acyclic --.

Claim 4, Column 8, line 27 - the correct ratio should read -- 9-15% C₂₄ -- instead of as shown in the patent.

Signed and sealed this 6th day of February 1973.
